DESIGN FOR A GERMICIDAL LAMP FIXTURE

Carl X. Meyer, St. Louis, Mo., assignor to Day-Brite Lighting, Inc., St. Louis, Mo., a corporation of Missouri

Application April 22, 1946, Serial No. 128,839

Term of patent 3½ years

(Cl. D48—19)

To all whom it may concern:

Be it known that I, Carl X. Meyer, a citizen of the United States and a resident of the city of St. Louis and State of Missouri, have invented a new, original, and ornamental Design for Germicidal Lamp Fixture, of which the following is a specification, reference being had to the accompanying drawing, forming part thereof.

Fig. 1 is a perspective view of a germicidal lamp fixture, showing my new design.

Fig. 2 is a top plan view of said fixture,
Fig. 3 is a front side elevational view of said fixture; and

Fig. 4 is an end view of said fixture looking at the opposite end from that shown in Fig. 1.

I claim:

The ornamental design for a germicidal lamp fixture, as shown.

CARL X. MEYER.
